UNITED STATES PATENT OFFICE.

THOMAS J. PHILLIPS, OF MCKEESPORT, PENNSYLVANIA, ASSIGNOR OF ONE-HALF TO
WILLIAM F. ORR, OF KITTANNING, PENNSYLVANIA.

SLED.

1,091,955.

Specification of Letters Patent. Patented Mar. 31, 1914.

Application filed March 8, 1913. Serial No. 753,058.

To all whom it may concern:

Be it known that I, THOMAS J. PHILLIPS, a citizen of the United States of America, residing at McKeesport, in the county of 5 Allegheny and State of Pennsylvania, have invented certain new and useful Improvements in Sleds, of which the following is a specification, reference being had therein to the accompanying drawing.

10 This invention relates to sleds, and the primary object of my invention is to provide a sled that resembles a miniature horse having the legs thereof provided with runners, some of which can be easily steered or 15 guided by the occupant of the sled.

Another object of this invention is to provide a sled with positive and reliable means, as hereinafter set forth, whereby the occupant of the sled can propel the same over a 20 horizontal sheet of ice.

A further object of this invention is to provide a sectional sled body resembling a miniature animal, the body having one section thereof pivoted whereby it can be shifted relatively to the other section of the body and consequently, the sled guided in a desired direction.

A still further object of this invention is to provide an ornamental sled that is simple in construction, durable, safe to use, and highly efficient for the purposes for 30 which it is intended.

With the above and other objects in view, the invention resides in a novel construction, combination and arrangement of parts to be hereinafter specifically described and then claimed.

Reference will now be had to the drawing, wherein:—

40 Figure 1 is a side elevation of the sled. Fig. 2 is a plan of the same. Fig. 3 is an elevation of a portion of the sled, partly broken away and partly in section, and Fig. 4 is an end view of the sled partly broken 45 away and partly in section.

A sled in accordance with this invention comprises a sectional body, the sections of which are designated 1 and 2. The sections 1 and 2 resemble the body of a horse or other 50 animal with the section 1 representing the shoulders, neck and head of a horse. This section is supported by arch shaped legs 3 provided with runners 4, and the head and neck of the section 1 are provided with side

handle bars 5, which are used to guide the 55 runners 4 in a desired direction.

The section 2 resembles the rear corners of a horse or other animal and said section is provided with a seat 6 and arch shaped legs 7 having rear runners 8.

60 The confronting ends of the sections 1 and 2 are provided with vertically alining tongues 9, best shown in Fig. 3 and these tongues are connected together by a vertical pivot pin 10. The rear end of the section 1 has beveled side walls 11 adapted to be engaged by beveled flanges 12, carried by the forward end of the body 2. The walls 11 and the flanges 12 limit the movement of the section 1 relatively to the section 2 70 when the sled is being guided over a surface.

Secured to the bottom side of the section 2, below the seat 6, by screw bolts 13 or other fastening means is a depending housing 14. 75 The housing 14 is provided with a central longitudinal slot 15 and with side slide head openings 16. The lower walls of the housing 14 are slotted, as at 17 and slidably mounted in the openings 16 are slide heads 18. These slide heads are retained in engagement with the housing by coiled retractile springs 19 arranged in the inner ends of the openings 16. The slide heads 18 support a revoluble transverse crank 80 shaft 20, said shaft having the outer ends thereof provided with cranks 21, and roller pedals 22. The shaft 20, intermediate the ends thereof and within the slot 15 is provided with a propelling wheel 23 and the 90 periphery of this wheel has equally spaced detachable teeth 24 adapted to engage in a smooth surface as the surface of ice whereby the sled can be moved over the same.

The coiled retractile springs 19 hold the 95 propelling wheel 23 normally out of engagement with the surface upon which the sled rests, but an occupant of the seat 6 can easily place the feet upon the pedals 22, lower the shaft 20 and revolve the same 100 whereby the propelling wheel 23 will engage the surface upon which the sled rests. The sled can be easily moved over the surface, somewhat similar to a velocipede, and by guiding the section 1 of the body, the sled 105 can be moved in a desired direction.

While in the drawing, there is illustrated a preferred embodiment of the invention, it

is to be understood that the structural elements are susceptible to such variations and modifications as fall within the scope of the appended claim.

5 What I claim is:

A sled comprising a body formed of a front and rear section pivotally connected together, runners supporting each of said sections, a housing secured to and depending from said rear section and formed with slots in the lower portion thereof, vertically movable slide heads within said housing, extensible and contractible springs having

one end anchored to the housing and their other ends secured to said slide heads, a 15 crank shaft extending through said housing and journaled in said heads, said slots providing clearance for said shaft, and a toothed wheel arranged centrally of said housing and fixed to said shaft.

In testimony whereof I affix my signature in the presence of two witnesses.

20 THOMAS J. PHILLIPS.
